UNITED STATES PATENT OFFICE.

SPIRO DENIS GARBIS, OF CALCUTTA, BRITISH INDIA.

MOUTHPIECE FOR LIQUID-RECEPTACLES.

1,384,315.

Specification of Letters Patent.

Patented July 12, 1921.

Application filed October 27, 1920. Serial No. 420,001.

To all whom it may concern:

Be it known that I, SPIRO DENIS GARBIS, a subject of His Majesty the King of Greece, and whose address is 90 Lower Circular 5 road, Calcutta, British India, have invented Mouthpieces for Liquid-Receptacles, of which the following is a specification.

The object of this invention is an improved cap or mouthpiece for a petrol tin or 10 the like.

The cap and mouth-piece now used with petrol tins is heavy and clumsy. The cap, moreover, is likely to be stolen being made of brass. This is especially likely to occur 15 in transit by rail when the tins are being sent back empty to be refilled.

The caps at present in use also labor under the disadvantage that they sometimes get jammed onto the mouthpiece and the tin can- 20 not be easily opened. The usual method of sealing adopted is to use a piece of wire passing through some part of the cap se- 25 cured with a lead seal in such a way that the cap cannot be opened until the seal is broken.

In breaking the wire the little lead seal is 25 itself usually thrown away so that there is a small recurring expense in replacing these seals each time the tin is refilled.

The object of this invention is to provide 30 a type of cap which cannot be stolen.

Another object is to provide a type of seal which need not be broken to extract the contents of the tin and which seal will in general return to the firm refilling the tin. The 35 lead of the seal can thus be recovered, and the wire also if desired, thus avoiding even the little loss which the provision of new lead seals at each refilling entails.

In closing the tin a disk of lead, leather, 40 rubber or any other suitable material is used. This disk is protected against damage by the projecting edge of the mouthpiece, but can be easily pierced with a blunt tool like a screw-driver, cut out with a pen-knife or 45 otherwise punctured. Such puncturing of the closing disk is immediately apparent to the eye.

The closing disk may be inserted by bending it and depressing it into the mouthpiece 50 and springing it into place, the fastening ring being slackened back a suitable amount to allow of this being done.

A preferred arrangement however, is by 55 providing a slot through the side of the mouthpiece approximately level with the top

of the upper surface of the tin itself, such slot being wide enough for the closing disk to be slipped into place from the side.

The closing disk is held in position by a screw down fastening ring which is itself 60 sealed by the wire and lead seal referred to above. The extraction of the contents of the tin can only occur if either the closing disk is punctured or the fastening ring is tampered with.

The fastening ring may be provided with one or more small rings, knobs or other means to or around which the sealing wire may be fastened or looped before passing through the holes in the sides of the mouth- 70 piece. By putting a strain on such wire before sealing the slackening back of the fastening ring can be absolutely prevented until the seal is broken.

My invention will be described with ref- 75 erence to the accompanying drawings in which like numbers of reference indicate like parts throughout, and in which:—

Figure 1 is a part plan and part sectional plan of the apparatus;

Fig. 2 is a sectional elevation of the same.

In these figures the mouthpiece 1 has a cylindrical part 2 which is screwed internally to take a fastening ring 5. This fastening ring is prevented from being removed 85 altogether by an internally projecting flange 4. A bottom flange 6 is soldered or otherwise secured to the inner end of the mouth- 90 piece or may be one piece with the same and provides the shoulder against which the fastening ring presses the closing disk 7. This closing disk may be made of lead, leather or any suitable substance to prevent leakage 95 of the contents of the tin.

The mouthpiece is soldered into the top of 95 the tin, can or receptacle 8 to which it is to be applied.

Various methods may be provided for unscrewing the fastening ring 5 sufficiently to release the closing disk 7 when the same is 100 to be renewed when the tin is to be re-filled.

One such method is shown at 9, 9 on Fig. 1. In this modification a number of out- 105 wardly extending notches are made in the interior surface of the fastening ring into which notches a convenient instrument can be fitted to turn the ring.

According to another modification a slot or notch 10 may be made in the upper sur- 110

face of the ring into which the end of a screw-driver can be fitted for the desired purpose.

In another modification holes 11 may be 5 made in the ring into which holes the ends of some spring actuated instrument may fit adapted to unscrew the ring.

For sealing the ring two or more small holes 12, 12 may be provided which may be 10 positioned so as to be clear only when the fastening ring is screwed down securely onto the closing disk. Through these holes the ends of a piece of wire may be passed, the ends twisted together and a lead or other 15 seal applied in the usual manner. If preferred this seal can be arranged to lie inside the mouth of the mouthpiece itself.

One or more small rings, projections or other means 13 may be provided on the fastening ring 5 to or around which the wire of 20 the seal may be passed before the same is passed through the holes 12. If more than one of these means 13 are provided there will always be one conveniently placed so 25 that the wire of the seal may be looped around the same and twisted so as to be tightened in such a manner that a slackening back of the fastening ring is altogether prevented until the seal is broken.

30 It will be noted that the provision of these means 13 allows of a certain amount of latitude in the positioning of the holes 12, which is a distinct advantage.

A slot 14 may be provided through the 35 side of the mouthpiece through which the closing disk 7 may be inserted.

It will be obvious that there are other 40 simple ways of sealing the fastening ring in position and I do not confine myself to the use of only the modification mentioned above.

I do not confine myself to the use of this cap to petrol tins only. It may be adapted for use with milk bottles or with cans or other receptacles for holding liquids.

Having now particularly described and ascertained the nature of my said invention and the manner in which the same is to be performed, I declare that what I claim is:—

1. A mouthpiece with means for closing 50 the same adapted for use with receptacles for holding liquids, characterized by having an internally screwed cylindrical part, a fastening ring adapted to engage such internal screw thread, an inwardly projecting flange on the outer or exterior end of the cylindrical portion to prevent removal of the fastening ring, an inwardly projecting flange at the inner or interior end of the cylindrical part adapted to form a shoulder 55 against which the fastening ring may compress and hold a closing disk, and a closing disk of suitable material.

2. A mouthpiece according to claim 1, with means whereby the same can be sealed 60 in such a manner that the fastening ring cannot be slackened back to allow of the contents of the receptacle being extracted unless such sealing means is broken, substantially as herein described.

3. With a mouthpiece according to claim 1, the use of a closing disk made of material which will retain the contents of the tin but which can be readily punctured in order to extract such contents.

4. A mouthpiece according to claim 1 but further characterized by having a slot substantially as herein described through which the closing disk may be introduced.

In testimony whereof I hereto affix my 80 signature.

SPIRO DENIS GARBIS.
